DESIGN FOR A POCKET PERFUME ATOMIZER OR SIMILAR ARTICLE

Leopold K. Kuhnl, Stratford, Conn.

Application February 12, 1948, Serial No. 144,446

Term of patent 14 years

(Cl. D83—1)

To all whom it may concern:

Be it known that I, Leopold K. Kuhnl, a citizen of the United States, residing at Stratford, county of Fairfield, State of Connecticut, have invented a new, original, and ornamental Design for Pocket Perfume Atomizer, or Similar Article, of which the following is a specification, reference being had to the accompanying drawing, forming part thereof.

Fig. 1 is a side view of a pocket perfume atomizer or similar article, showing my new design;

Fig. 2 is a front elevation taken from the left of Fig. 3, and

Fig. 3 is a top plan view thereof.

I claim:

The ornamental design for a pocket perfume atomizer or similar article, substantially as shown.

LEOPOLD K. KUHNL.
